UNITED STATES PATENT OFFICE.

FRANKLIN L. LANE, OF BELOIT, WISCONSIN, ASSIGNOR TO P. B. YATES MACHINE COMPANY, OF BELOIT, WISCONSIN, A CORPORATION OF WISCONSIN.

GAGE.

1,295,179.

Specification of Letters Patent. Patented Feb. 25, 1919.

Application filed June 24, 1918. Serial No. 241,483.

To all whom it may concern:

Be it known that I, FRANKLIN L. LANE, a citizen of the United States, residing at Beloit, in the county of Rock and State of Wisconsin, have invented certain new and useful Improvements in Gages, of which the following is a specification.

My invention pertains to gages or adjustment appliances especially, though not exclusively, adapted for use in connection with 10 woodworking machines, such as planers. It aims to provide simple means to facilitate the proper adjustment of the parts of such a machine to secure the planing of a board 15 of the desired thickness, whether one or more surfaces thereof are being operated upon. One of its leading objects is to secure a quick but accurate adjustment of the parts of the mechanism and obtain the planed or 20 finished board of the required thickness without measurement by means of rules, scales, or similar graduated instrumentalities. Simplicity in structure, economy in manufacture, ease and certainty of operation, rapidity of manipulation, exactness of 25 results, and other desirable objects, are attained in appliances embodying the features of the present invention.

In order that those skilled in this art may 30 have a full and complete understanding of the invention both from its structural and functional standpoints, I have illustrated a preferred embodiment of the same in the accompanying drawing forming a part of this 35 specification and throughout the views of which like reference characters refer to the same parts.

In this drawing:

Figure 1 is a fragmentary end view of a 40 planer equipped with the new appliance;

Fig. 2 is a fragmentary longitudinal section; and

Fig. 3 shows the apparatus in end elevation, illustrating a fragment of the planer 45 proper.

In these drawings no attempt has been made to show the details of the planing mechanism, since an understanding of the invention may be had from the more or less diagrammatic illustration presented. The 50 machine has the usual upper and lower sectional feed-rollers 11 and 12 and the upper

planer cylinder 13 equipped with the customary planing knives. If preferred, the machine may be a double surfacer employing also the lower, companion, planer-cylinder 14. Associated with these is the usual vertically-adjustable bed 15 which can be moved up and down by any suitable or customary means, screws 16 for this purpose 60 being shown more or less diagrammatically and fragmentarily.

At one side of the bed or platen a curved or other suitably-shaped bracket 17, by means of screws 18, 18, is fastened to or rigid 65 with the support or mounting for the upper feed-rollers and the corresponding planer-cylinder, and to this bracket a long bar 19 is pivoted or fulcrumed at 20, the other end of such bar being accommodated and guided 70 in a slotted bracket 21 fastened to the same support by screws 22 on the opposite side of the bed. It will be clear, therefore, that the bar transversely overlies the bed. The slot 23 of the bracket has an open top so that 75 the bar may be swung up and down a limited amount, the lower end of the slot ordinarily acting as a support for such end of the bar and as a stop to limit or restrict the downward swinging of the bar on its fulcrum, as 80 shown in dotted lines in Fig. 1.

Relatively near to the fulcrumed end of the bar, it is equipped with a block 30 having a threaded stem or shank 31 extended through a hole in the bar, such shank holding the block against the face of the bar by means of its two nuts 32, 32, located on the opposite side of the bar. This construction constitutes a pivotal or oscillatory mounting 90 for the block on the bar, but there is sufficient friction between the parts to prevent turning of the block except under intended manual action. The block has a threaded hole down through it receiving an adjustment or gage screw 33 with a knurled head 34 and a lock-nut 35. Adjacent to the block the bar has a projecting pin 36 against which the block may bear either in its operative upright position shown in full lines in Fig. 1, or in its inoperative inclined relation 95 in dotted lines in the same figure. Such adjustable gage screw is intended to be used in association with various size-blocks of known graduated thicknesses 100

which, of course, require no measurement, one of such blocks being shown in Figs. 1 and 3.

Assuming that it is desired to adjust the bed of the machine so as to plane a board to a predetermined thickness, the screw and its companion block are swung from the inclined dotted-line position of Fig. 1 to vertical position, the bar at this time resting on the bottom of the slot of bracket 21. Then a size-block, preferably of metal, of the same thickness as the desired finished board, is placed on the bed 15 beneath the screw, whereupon the bed is fed or adjusted upwardly until such rising size-block resting on the bed, by engagement with the lower end of the screw, raises the latter and the bar until the top edge of such bar is in register with the top surface of bracket 21 (Fig. 2). Now the screw is swung into inactive diagonal position, the size-block removed, and the bar permitted to drop to the bottom of the slotted bracket. The machine is now ready to plane a board to the required thickness, the gage-screw, of course, having been moved out of position sufficiently so as not to interfere with this action. When a single upper planing cylinder only is used, it will be understood that when the screw is upright and the top surface of the bar is in alignment or register with the corresponding face of the slotted bracket, the lower end of the screw will be in register with the lowermost part of the planing cylinder or one of its knives when in its lowermost position. When, however, the machine has a pair of planing cylinders for double surfacing, whereas the lower end of the gage screw may not be in exact register with the knives of the upper cylinder when in their lowermost position, nevertheless, it is in such position that if the bed is adjusted up to it with the proper interposed size-block, the bed will then be in position for the production of a double surfaced board of the required thickness.

Either in a single surfacer or double surfacer, if the knives have been ground or adjusted, in order to compensate for this action in the screw, it is merely necessary to run a board through the machine, then place it upon the bed, which has not in the meantime been disturbed, and turn the screw down until its lower end, by engaging the top surface of the board, causes the bar to rise until its edge and that of the slotted bracket are in register. Then the lock or clamping nut of the screw is tightened, and the board is removed, whereupon we may proceed to use the appliance in the usual manner.

To those skilled in this art it will be obvious that the invention is not limited and restricted to the precise and exact features of construction presented because these may

be modified in many minor details without departure from the substance of the invention and without the sacrifice of any of its substantial benefits and advantages.

In some cases the slotted bracket may be done away with, it being merely necessary to have some form of index for the bar to co-act with to indicate when the latter is in proper position. It will also be apparent that the appliance could be used in a machine in which the tool or planing cylinder is adjusted toward and from the bed instead of the bed moved toward and from the tool. Obviously, also, instead of using brackets 17 and 21 separate from and fastened to the mounting or support for the pressure-rollers and planer-cylinders, they may be made integral parts of said mounting.

It will be appreciated that in the particular embodiment of the invention set forth in this application, it is desirable to locate the gage screw and its block near the pivoted or fulcrum end of the cross-bar, whereby the adjustments of the screw will be magnified or many times increased at the free end of the bar, thus assuring great accuracy in the use of the appliance. Obviously, such an arrangement is not absolutely essential as the screw may be located at any desirable point along the length of the bar or any other suitable and convenient means for obtaining an accurate adjustment may be employed.

I claim:

1. An appliance of the character described adapted for use with planing, surfacing, and similar machines with tools and beds for the work adjustable relatively to one another, comprising in combination, a bracket adapted to be fastened to the mounting for the tool, a bar pivoted near one end to said bracket and adapted to overlie the bed of the machine, a slotted guide-bracket adapted to be secured to said tool mounting and co-act with the opposite end portion of said bar, a block pivoted on said bar and arranged to be swung into operative and inoperative position, a stop-pin with which said block is adapted to co-operate, a gage-screw adjustable in said block toward and from the machine-bed, and means to lock said gage-screw in adjusted position, substantially as described.

2. An appliance of the character described adapted for use in planing, surfacing, and similar machines with tools and beds for the work adjustable relatively to one another, comprising in combination, a bracket adapted to be fastened to the mounting for the tool, a bar pivoted near one end to said bracket and adapted to overlie the bed of the machine, a slotted guide-bracket adapted to be secured to said tool mounting and co-act with the opposite end portion of said bar, a block pivoted on said bar and ar-

- ranged to be swung into operative and inoperative position, a gage-screw adjustable in said block toward and from the machine-bed, and means to limit the turning of said block to maintain said screw at right-angles to said bed, substantially as described.
3. An appliance of the character described adapted for use in planing, surfacing, and similar machines with tools and beds for the work adjustable relatively to one another, comprising in combination a support adapted to be fastened to the mounting for the tool, a bar pivoted to said support and adapted to overlie the bed of the machine, a slotted guide-bracket coöperating with said bar, and a gage-member on said bar adjustable toward and from the bed of the machine and adapted to co-act with size-blocks on said bed, substantially as described.
4. A thickness gage appliance of the character described adapted for use on planing, surfacing, and similar machines with tools and beds for the work adjustable relatively to one another to vary the thickness of the finished product comprising in combination, a thickness gage-member, means to support said gage-member on the mounting of the tool positioning the gage-member over said bed, means to adjust said gage-member toward and from the bed, and means permitting the gage-member to be shifted into an inoperative position during the action of the tool on the work, substantially as described.
5. A thickness gage-appliance of the character described adapted for use on planing, surfacing and similar machines with tools and beds for the work adjustable relatively to one another to vary the thickness of the finished product comprising in combination, a bar adapted to overlie the bed of the machine, means adapted to movably support said bar on the mounting of the tool, a thickness gage-member on said bar, and means permitting said gage-member to be shifted into an inoperative position during the action of the tool on the work, substantially as described.
6. A thickness gage appliance of the character described adapted for use on planing, surfacing and similar machines with tools and beds for the work adjustable relatively to one another to vary the thickness of the finished product comprising in combination, a bar adapted to overlie the bed of the machine, means adapted to movably support said bar on the tool mounting, a thickness gage-member on said bar adjustable toward and from the bed of the machine, and means permitting the gage-member to be shifted to an inoperative position during the action of the tool on the work, substantially as described.
7. A thickness gage appliance of the character described adapted for use on planing,
- surfacing and similar machines with tools and beds for the work adjustable relatively to one another to vary the thickness of the finished product comprising in combination, a bar adapted to overlie the bed of the machine, means adapted to pivotally support said bar on the tool mounting, a thickness gage-member on said bar adjustable toward and from the bed of the machine, and means permitting the gage-member to be shifted into an inoperative position during the action of the tool on the work, substantially as described.
8. A thickness gage appliance of the character described adapted for use on planing, surfacing and similar machines with tools and beds for the work adjustable relatively to one another to vary the thickness of the finished product comprising in combination, a bar adapted to transversely overlie the bed of the machine, means to pivotally support said bar at one end only on the tool mounting, a thickness gage-member on said bar adjustable thereon toward and from the bed of the machine, and a mounting for said gage-member on said bar permitting the member to be moved into an inoperative position during the action of the tool on the work, substantially as described.
9. A thickness gage appliance of the character described adapted for use on planing, surfacing and similar machines with tools and beds for the work adjustable relatively to one another to vary the thickness of the finished product comprising in combination, a bar adapted to overlie the bed of the machine, means adapted to pivotally support said bar on the tool mounting, and a thickness gage-member adjustable on said bar toward and from the bed of the machine and pivoted thereon to permit it to be swung into an inoperative position during the action of the tool on the work, substantially as described.
10. A thickness gage appliance of the character described adapted for use on planing, surfacing, and similar machines with tools and beds for the work adjustable relatively to one another to vary the thickness of the finished product comprising in combination, a thickness gage-member, means to support said gage-member movably on the mounting of the tool positioning the same over said bed, whereby the member may co-operate with a size-block on the bed, and an indicator operated during the adjustment of the bed and tool relatively to one another by said size-block through said gage-member adapted to show when the bed and tool are positioned relatively to one another to produce a product of the thickness of the size-block coöperating with the gage-member and the said indicator being constructed to augment the movements of the gage-member thereby permitting a fine adjustment of the

bed and tool with relation to one another, substantially as described.

11. A thickness gage appliance of the character described adapted for use on planing, surfacing, and similar machines with tools and beds for the work adjustable relatively to one another to vary the thickness of the finished product comprising in combination, a thickness gage-member, means to support said gage-member movably on the mounting of the tool positioning the same over said bed, whereby the member may co-operate with a size-block on the bed, an indicator operated during the adjustment of the bed and tool relatively to one another by said size-block through said gage-member adapted to show when the bed and tool are positioned relatively to one another to produce a product of the thickness of the size-block coöperating with the gage-member and the said indicator being constructed to augment the movements of the gage-member thereby permitting a fine adjustment of

the bed and tool with relation to one another, and means to permit the gage-member to be shifted into an inoperative position during the action of the tool on the work, substantially as described. 25

12. A thickness gage appliance of the character described adapted for use on planing, surfacing, and similar machines with tools and beds for the work adjustable relatively to one another to vary the thickness of the finished product comprising in combination, a thickness gage-member, means to support said gage-member movably on the mounting of the tool positioning the same over said bed, whereby the member may co-operate with a size-block on the bed, and an indicator actuated by said gage-member adapted to show when the bed and tool are positioned relatively to one another to produce a product of the thickness of the size-block coöperating with the gage-member, substantially as described. 30 35 40
